UNITED STATES PATENT OFFICE.

JAMES C. DOZIER, OF BATON ROUGE, LOUISIANA.

DRIER.

1,310,858.

Specification of Letters Patent. Patented July 22, 1919.

Application filed February 5, 1919. Serial No. 275,177.

To all whom it may concern:

Be it known that I, JAMES C. DOZIER, a citizen of the United States, residing at Baton Rouge, in the county of East Baton Rouge and State of Louisiana, have invented certain new and useful Improvements in Driers, of which the following is a specification.

This invention relates to certain new and useful improvements in apparatus for drying, designed more particularly for the drying of lumber, although as the description proceeds it will be observed that the invention is not necessarily restricted to such use.

Heretofore driers employing endless carriers have been designed for the drying of grain and other materials wherein provision was made for the introduction of hot air, but in such devices the hot air was allowed to ascend perpendicularly, no floors or other analogous means being provided in the interior of the drier to direct the flow of the hot air.

One of the main objects of my invention is to provide a drier of this general character employing an endless conveyer system, but so constructed that the various compartments are separated by floors or other analogous means, each compartment having an opening in the floor at one end, and the floor of the next compartment or what may be termed the ceiling of the first named compartment provided with an opening at the opposite end whereby the hot air is caused to circulate horizontally back and forth through the various compartments as it ascends to the top. By this means the air is caused to take a zig-zag or circuitous path whereby the material being dried is subjected to the influence of such hot air throughout its passage through the drier.

At alternately opposite ends of the various compartments, I provide guide bars arranged at such a predetermined angle as to cause the material, such for instance as lumber, when discharged from the conveyer to strike the adjacent guide bar before it comes into contact with the conveyer in the next compartment, so that when the board slides down the bar until its lowest edge comes in contact with the chain, it serves to stop the board on the conveyers square with

them, that is one end of the board will not be in advance of the other end; so that the board is carried from one end to the other 55 in a plane at right angles to the conveyer.

I provide a conduit or duct for admission of the air at the lower end of the drier, as well as a fan or blower for forcing hot air into the lowermost compartment. Either 60 or both of these last named provisions may be employed as circumstances may require.

Other objects and advantages of the invention will hereinafter appear, and the novel features thereof will be particularly 65 pointed out in the appended claims.

The invention, in its preferred form, is clearly illustrated in the accompanying drawings which, with the numerals of reference marked thereon, form a part of this 70 specification and in which—

Figure 1 is a longitudinal sectional elevation of a drier constructed in accordance with my present invention;

Fig. 2 is a sectional perspective view looking at one end of the drier, the section being at right angles to that shown in Fig. 1.

Like numerals of reference indicate like parts in the different views.

Referring to the drawings 1 designates 80 the drying chamber which may be of any desired dimensions, the same being closed at the top as at 2 and provided with the flue 3 for the escape of the hot air.

Within the drying chamber or inclosure 1 85 are a plurality of endless conveyers 4 arranged to move alternately in opposite directions, as indicated best by the arrows in Fig. 1. These conveyers may be of any well-known or preferred form adapted to the 90 purpose, and each conveyer is mounted upon sprockets 5 and 6, one at each end of the drying chamber, the shafts 7 and 8 of these sprockets being mounted in suitable bearings 9, as seen best in Fig. 2.

In order to impart the necessary motion to the sprockets 5 and 6, and thence to the conveyers 4, I provide a main power shaft 11, secured to the drying chamber by brackets 12, and preferably extending longitudinally of the chamber. Extending perpendicularly of the chamber, approximately at each end and adjacent the sprockets 5 and 6 respectively, are two shafts 13 and 14,

mounted in suitable bearings. These shafts 13 and 14 are provided with miter gears 15 and 16, meshing respectively with pinions 17 and 18, secured to the shaft 11. Adjacent the sprockets 5 and 6, the shafts 13 and 14 are provided with beveled gears 19 and 20, meshing with coöperating gears 21 and 22, fixed upon the shafts 7 and 8 respectively. The gears 19 and 21 are shown in Fig. 2, the gears 20 and 22 not being shown in that figure, but the construction will be readily understood.

By inspection of Fig. 1, it will be noted that the chamber 1 is divided into a plurality of longitudinally extending compartments, for a purpose to be hereinafter explained. It will be evident that each compartment carries an endless conveyer. A power belt 23 is applied to the power wheel 20 or pulley 24, fixed to the shaft 11. The gear 17 is at the left of the gear 15, and the gear 18 at the right of the gear 16. Consequently, when the belt 23 rotates the wheel 24 in the direction of the arrow, Fig. 1, the shaft 13 will be rotated to the left, and the shaft 7 will also be rotated to the left, as will be understood. It will be clear therefore that the shafts 14 and 8 will simultaneously be turned to the right. This rotation of the shafts 7 and 8 causes a constant pull to be exerted on the tops of the conveyers 4, whether they are traveling to the left, as in the top compartment, or to the right, as in the compartment just below, etc. This construction facilitates the utilization of the necessary flexible conveyers, such as chains, or belts, etc., keeping them tight at the top, where the material rests.

I have shown the chamber 1 divided into a plurality of compartments A, B, C, D and E. Manifestly as many compartments may be provided as are desired. In each compartment however there is mounted, as indicated, one set of traveling endless conveyers 4.

To facilitate feeding of the material to the chamber 1, the topmost conveyer extends outwardly therefrom, as shown in Fig. 1. The sprocket 6, carrying the conveyer 50 for the chamber A, is therefore mounted outside of the chamber 1, and is supported by the bracket 25, the conveyer 4 passing into and out of the chamber through suitable slots provided for this purpose. The 55 conveyers in each compartment are preferably directly under the conveyers in the compartment directly above, there preferably being two sets of conveyers located in each compartment, as shown in Fig. 2.

Power is preferably applied to only one end of the conveyer set in each compartment, and by the word "set" I include any installation embodying one or more conveyers. In the present instance, it will be noted that, in the chamber A, power is ap-

plied at the left end, and at the right end in chamber B, etc. In each chamber, the end of the conveyer remote from the point where power is applied, is offset toward the end wall of the chamber 1, as shown in Fig. 70 1. In other words, the power sprockets of the chambers A, C, and E are in vertical alinement on the left, and those of the chambers B, D, and F are in similar alinement on the right. The same is true of the 75 idler sprockets, or those to which the power is not applied, the idler sprockets of A, C, and E being in alinement, but offset toward the left from the plane of the power sprockets. There are only two idler sprockets 80 shown in alinement at the right, the sprocket 6, for the top conveyer, extending outside of the chamber, as described.

Each compartment is provided with a floor, which manifestly forms what might 85 be termed the roof or top of the compartment directly underneath. The compartment A is provided with a floor A', forming the top of the compartment B, and the floor B' of the compartment B provides a top for 90 the compartment C, etc. At the end adjacent the power sprocket, each of the floors A', B', etc., is provided with a laterally extending opening just above the idler sprocket located in the compartment below. An inspection of Figs. 1 and 2 of the drawings, 95 in connection with the foregoing, should make clear the construction and disposition of the gearings, compartments, conveyers, etc.

Mounted adjacent and on either side of the sets of power sprockets in each compartment, are guide bars 26, it being understood that, since four power sprockets are here described in each compartment, there 105 is a guide bar 26 on either side of each set of two power sprockets, as shown in Fig. 2. The bars 26 are preferably, although not necessarily, fixed to the side walls of the chamber 1, extending downwardly through 110 the openings in the floors, and inwardly beneath the power sprockets of the compartment above, resting on the floor of the compartment beneath. Since the idler sprockets are behind the bars 26, in each compartment, as shown in Fig. 1, it is evident that in the compartment A, material will fall from the conveyer against the bars 26, and slide downwardly on said bars and onto the conveyer in the compartment B, the bars 115 causing the material to assume a straight transverse position on the conveyers. A similar action will take place in all the compartments until the material passes out of the chamber on the guide bars 27, through 120 the opening 28 provided for this purpose.

The invention contemplates the subjection of the interior of the chamber 1 to the action of a drying medium, such as hot air. In the accomplishment of this purpose, I have 125 130

shown the chamber mounted on a foundation which provides a conduit G directly beneath the floor of the lowermost compartment. In usual practice this conduit may be made of bricks or concrete.

The invention is here shown adapted for use in drying lumber. In drying lumber of certain kinds, where only a slow circulation of air is required, I install steam pipes 29, 10 29, on the floor of the conduit, admitting air through the opening 30 at the left, as shown in Fig. 1, and depending upon the natural tendency of the heated air to rise and pass through the several compartments in the 15 chamber 1 and out through the flue 3. In drying other kinds of lumber however, where a more rapid circulation of the medium is necessary, the steam to the coils may be shut off, and I may use a blower, so connected as to be adapted to deliver a hot blast of air into the opening 30, and thence into the chamber 1, through the opening in the floor F', at the right. The object in driving the heating medium through the full length 25 of the conduit is to permit the expansion and equal distribution of its heat, before it enters the lower compartment F.

From the foregoing it is believed that the operation of the apparatus will be clear. In 30 the construction herein shown, the conveyer in the compartment A is moving to the left, in order to bring the lumber x into the chamber 1. It will be evident therefore that the conveyers of compartments A, C and E, are 35 all moving to the left, and those of the alternate compartments, B, D and F are traveling to the right. The drying medium enters the chamber 1 through the opening at the right end of floor F', and travels to the left 40 through the compartment F, and longitudinally thereof; thence through the opening at the left of the floor E', and travels to right through the compartment E, and longitudinally thereof. This tortuous path of 45 travel of the drying medium is maintained through the successive compartments, until it passes out the flue 3. It will be noted that, in each compartment, the direction of travel of the drying medium is opposite to the direction of travel of the material being 50 treated. The respective directions of travel of the drying medium and of the material, and the relative location of the feeding opening for the material and for the medium, is of especial importance. The green or untreated lumber enters the chamber from the top, and the heating medium from the bottom, in its dry form. In ascending 55 through the several compartments the medium will gradually become more or less saturated by moisture drawn from the material, and when it reaches the topmost conveyer the medium will have assumed the condition of a hot vapor. The lumber passing 60 through the heated vapor in the upper

compartments will be subjected to a virtual steam bath which will tend to open the pores thereof, so that, upon reaching the drier medium in the lower compartments, the lumber will be in condition to be 70 thoroughly dried from the center outwardly, thereby preventing the unequal shrinkage, the usual cause of seasoning cracks which greatly damage the material. The passage 75 of the drying medium in a direction opposite to the travel of the material being treated, tends to drive the medium into the opened pores of the wood, as will be readily understood. If the material and medium are traveling in the same direction the same 80 action would not take place, as the dry medium must, in this case, be allowed to enter with the raw material, and travel along and pass out with it. It will be noted therefore, with such a structure, the raw moisture-containing material would be subjected 85 to the dry medium at the outset, and to a saturated medium immediately prior to leaving the chamber, which would defeat the object of the invention, as explained. It is important that the material be first subjected 90 to a more or less saturated medium, and thereafter to a dry medium, before it leaves the chamber.

Various modifications may be resorted to 95 by those skilled in the art, but my invention includes all such embodiments as fall fairly within the scope of the appended claims.

What I claim as new is:—

1. A drier comprising a chamber, a plurality of endless conveyers therein, a partition above and below each conveyer, each partition having therein an opening at one end for the passage of the air to the next higher compartment, said openings being 100 alternately arranged at opposite ends of the chamber, and guide bars arranged alternately at opposite ends of the chamber, said guide bars being disposed at an angle to the travel of the conveyers and traversing the 105 space between each two adjacent conveyers.

2. A drier comprising a chamber, having a plurality of superimposed compartments with an open space in the floor at one end of each compartment to provide for continuous circulation of ascending hot air admitted to the lowermost compartment, an endless conveyer in each compartment, and inclined guide bars alternately oppositely inclined at opposite ends and each extending 110 into two adjacent compartments.

3. A drier for lumber comprising a chamber provided with a plurality of superposed compartments, two sets of conveyers in each compartment, means for causing the conveyers in each compartment to travel in opposite directions, and guide bars positioned adjacent the take-off ends of each set of conveyers and extending below said conveyer sets into the compartment underneath, 115 120 125 130

whereby the lumber is delivered in alinement to the conveyer sets below, substantially as described.

4. A drier for lumber comprising a chamber provided with a plurality of superposed compartments, two sets of conveyers in each compartment, means for causing the conveyers in each compartment to travel in opposite directions, inclined guide bars posi-

tioned on either side of the ends of the conveyers in each compartment, and extending into the compartment below, whereby the lumber is delivered from a conveyer to the guide bars, is placed in alinement thereon, and is delivered in alinement to the conveyer set below, substantially as described.

In testimony whereof I affix my signature.

JAMES C. DOZIER.
